UNITED STATES PATENT OFFICE.

JAMES B. ROGERS, OF CHICAGO, ILLINOIS.

SPARK PLUG.

Application filed July 25, 1921. Serial No. 487,327.

To all whom it may concern:

Be it known that I, JAMES B. ROGERS, a citizen of the United States, residing at Chicago, in the county of Cook and State of Illinois, have invented new and useful Improvements in Spark Plugs, of which the following is a full, clear, concise, and exact description, reference being had to the accompanying drawing, forming a part of this specification.

My invention relates to spark plugs.

One of the objects of my invention is to provide an improved spark plug, in which means are provided for preventing twisting the central conductor within the insulating core or body.

A further object of my invention is to provide an improved spark plug provided with a metallic sheath surrounding the insulating core, and with a swivel ring bearing on this sheath to secure the plug in place.

A further object of my invention is to provide improved packing means at the end of the central conductor which extends through the insulating core.

A further object of my invention is to provide an improved spark plug having a metallic sheath surrounding the insulating core, with this metallic sheath carrying one of the electrodes.

A further object of my invention is to provide an improved spark plug which will be durable and efficient in operation, simple in construction and cheap to manufacture.

Further objects will appear from the detailed description to follow and from the appended claims.

In the drawings in which two embodiments of my invention are shown—

Figure 1 is a central axial section through a spark plug;

Fig. 2 is a section on the line 2—2 of Fig. 1;

Fig. 3 is a section on the line 3—3 of Fig. 2;

Fig. 4 is a detail perspective view of a split ring;

Fig. 5 is a detail view showing the mounting of one of the electrodes, and

Fig. 6 is a view showing a modification.

Referring first to Figs. 1 to 5 inclusive, the spark plug shown therein comprises an insulating base or core 10, an electrode 11 mounted at the inner end of the core 10, a wiring terminal construction 12, mounted at the outer end of the core 10, a conductor 13, electrically connecting the electrode 11 and the wiring terminal 12, a metal sheath

14 surrounding the enlarged central portion of the core 10, an electrode 15 carried by the sheath 14, a threaded ring or sleeve 16 swiveled on the sheath 14, and a bushing 17 into which the swivel ring 16 is screwed. The bushing 17 has a threaded portion 18 which may be screwed into the cylinder head to bring the electrodes 11 and 15 into the desired position. Suitable packing washers 19 and 20 may be provided between the sheath 14 and the insulating core 10 to prevent the escape of gas and to provide a cushion between the metal and porcelain. A suitable packing washer 21 may be provided between the sheath 14 and the bushing 18. These packing washers may be of any suitable material, and may be of the type known as copper asbestos washers. Also, a suitable packing washer 22 may be provided at the inner end of the core 10, between the shoulder portion 23 of the central conductor 13, and the shoulder portion 24 on the porcelain core to prevent the escape of gas at this point and to provide a cushion between the metal and porcelain.

In order to relieve the central conductor 13 from any twisting strain, due to the screwing down or up of the binding screw 25, means 26 are provided at the upper end of the insulating core 10, to hold the central conductor 13 against rotation inside of the core 10. This means comprises a washer member 27 having a central key-hole shaped opening 28, through which the central conductor 13 extends, the central conductor 13 having a flattened portion 29 at the point where it extends through the washer, which flattened portion lies in the elongated portion of the key-hole slot, so that relative rotation between the conductor and washer is prevented. Relative rotation between the washer and porcelain core 10 is prevented by means of downwardly extending projections 30 on the washer which fit into notches 31 (Fig. 3) in the porcelain core. Thus relative rotation is prevented between the central conductor 13 and the porcelain core 10. A sealing compound of cement may be provided at the upper end of the insulating core 10, as indicated at 32, to further effectually seal the connection between the central conductor 13 and the porcelain core 10 at this point.

In assembling the central conductor 13 with respect to the porcelain core 10, the central conductor carrying the electrode 11

and the washer 22 is inserted into the central opening in the porcelain core, the cement is placed as indicated at 32, the washer 27 is slipped over the end of the threaded ends of the conductor 13 (the enlarged portion 33 of the key-hole opening permitting this assembly) and the washer is then slipped sidewise to bring the flattened portion 29 of the central conductor into the narrow portion of the key-hole slot to prevent relative rotation between the washer and conductor. The washer 27 is then fitted to the core 10 so that the lugs 30 will enter the notches 31, and the holding nut 34 is then screwed down to draw the central conductor 13 firmly into place. As the nut 34 is screwed down, the shoulder 23 of the central conductor is caused to be drawn snugly against the packing washer 22 at the inner end of the core to effect a tight connection at this point. Drawing down the nut 34 also forces the washer 27 firmly into place, and also compacts the cement at 32 (which has not yet hardened). The electrodes 11 and 15 may be of iridium, tungsten or other metals having a high melting point, spot-welded to their supporting members. For this purpose, the electrode 11 is provided with a shank portion 35, which extends into a recess or socket in the end of the conductor 13. After the electrode is in place, it may be spot-welded or otherwise suitably secured. The electrode 15 is provided with an enlarged portion 36 at its upper end (Fig. 5) which lies in a suitable notch or recess 37 in the skirt portion of the sheath 14. After the electrode 15 has been placed in position with respect to the sheath 14, it may be secured in place by pressure and spot-welding, or in any suitable manner.

The swivel ring 16 may be held in place on the sheath 14 by means of a split ring 37, which can be sprung into place into an annular channel in the sheath. This split ring 37 keeps the swivel sleeve 16 in place on the sheath 14. If desired, an anti-friction ring 38 may be provided between the shoulder 39 of the sheath 14 and the lower edge of the swivel sleeve 16.

It will be noted that both of the electrodes are mounted on the central core 10 so that the adjustment is not disturbed when the central core 10 is removed from the bushing 17 for cleaning, etc. so that no readjustment of the electrodes is necessary in reassembly.

It will also be noted that the construction shown is in effect a complete spark plug without the bushing 17, as the bushing 16 may be, if desired, screwed directly into the head of the cylinder as shown in Fig. 6. In Fig. 6 the construction may be substantially the same as that shown in Fig. 1, except that the bushing 17 is omitted, and the swivel

sleeve 16 is screwed directly into the cylinder head 40. In this construction, the cylinder head is provided with a shoulder portion 41 against which the packing ring 21 bears, and is provided with an internally threaded portion 42, into which the swivel ring 16 screws.

It will be seen that in both constructions is provided a plug which can be connected and disconnected simply by screwing in or out the swivel ring 16, and in which it is not necessary to take the plug apart for cleaning, and in which there is no danger of any twisting strain being exerted on that portion of the central conductor 13 which lies inside the porcelain core, and in which provision is made for preventing the escape of gas, and for cushioning the engagement between the metal parts and the porcelain.

Having thus described my invention, what I claim as new and desire to secure by Letters Patent of the United States is:—

1. A spark plug construction comprising an insulating body, an electrode at one end thereof, a wiring terminal at the other end thereof, a conductor extending axially through said insulating body, and electrically connecting said electrode and wiring terminal, said insulating body having an enlarged portion, a metal sheath embracing and surrounding said enlarged portion, said metal sheath having two annular shoulders, one facing outwardly, and the other facing inwardly, a sleeve surrounding and swiveled on said sheath and bearing on said outwardly facing shoulder, a member having an outwardly facing annular seat, an annular gasket on said seat, said member and sleeve being provided with interengaging means whereby swiveling movement of said sleeve about said sheath will force the sleeve inwardly, to force the inwardly facing shoulder on the sheath into sealing engagement with said gasket; and to force the gasket into sealing engagement with the seat on said member.

2. A spark plug construction comprising an insulating body, an electrode at one end thereof, a wiring terminal at the other end thereof, a conductor extending axially through said insulating body and electrically connecting said electrode and wiring terminal, said insulating body having an enlarged portion, a metal sheath embracing and surrounding said enlarged portion, said metal sheath having two annular shoulders, one facing outwardly and one facing inwardly, a sleeve surrounding and swiveled on said sheath and bearing on said outwardly facing shoulder, means on said sheath for holding said threaded sleeve against movement away from said shoulder, a member having an annular outwardly facing seating shoulder, an annular gasket on said shoulder, said member and sleeve being

provided with interengaging means whereby swiveling movement of said sleeve about said sheath will force the sleeve inwardly, to force the inwardly facing shoulder on the 5 sheath into sealing engagement with said gasket and to force said gasket into sealing engagement with the outwardly facing shoulder on said member.

3. A spark plug construction comprising
10 an insulating body, an electrode at one end thereof, a wiring terminal at the other end thereof, a conductor extending axially through said insulating body, and electrically connecting said electrode and wiring
15 terminal, said insulating body having an enlarged portion, a metal sheath embracing and surrounding said enlarged portion, said metal sheath having two annular shoulders,

one facing outwardly, and the other facing inwardly, an electrode carried by said sheath for cooperation with said first electrode, a sleeve surrounding and swiveled on said sheath and bearing on said outwardly facing shoulder, a member having an outwardly facing annular seat, an annular gasket 25 on said seat, said member and sleeve being provided with interengaging means whereby swiveling movement of said sleeve about said sheath will force the sleeve inwardly, to force the inwardly facing shoulder on the 30 sheath into sealing engagement with said gasket, and to force the gasket into sealing engagement with the seat on said member.

In witness whereof, I have hereunto subscribed my name.

JAMES B. ROGERS.
